099-8

AU 291 EX
OR D 11,303

Design No. 11,303, dated July 22, 1879

UNITED STATES PATENT OFFICE.

CHARLES H. LEARNED, OF MERIDEN, CONNECTICUT.

DESIGN FOR FUNERAL ORNAMENTS.

Specification forming part of Design No. 11,303, dated July 22, 1879; application filed June 20, 1879.
[Term of patent 7 years.]

To all whom it may concern:

Be it known that I, CHARLES H. LEARNED, of Meriden, in the county of New Haven and State of Connecticut, have invented a new Design for a Metallic Funeral Ornament; and I do declare the following, when taken in connection with the accompanying illustration, to be a full, clear, and exact description of the same.

The invention relates to a design for an ornament with special reference to funeral decoration—that is to say, an ornament which may be attached to a casket, or to a coffin, or to flowers, or to other parts of funeral decoration, and for analogous purposes; and it consists in the form and ornamentation of a cross as the base, combined with the representation of a band or ribbon on and across its surface, with the representation on or at the sides of the cross of lily or calla flowers, with the representation of wheat, and a fuchsia flower, and lily and myrtle leaves, as represented in the accompanying illustration.

On the face of the ribbon or band any appropriate word or words may be placed. The lily flowers may be dispensed with, and the ornament consist of the cross and ribbon or band. The exact form of the ribbon or band is immaterial, it only being necessary that some form of a band or surface be represented on or across the surface of the cross suitable to bear an inscription or motto, (and represented as not a part of the cross itself.) The representation of the ribbon or band may be dispensed, with and the ornament consist of the cross and representation of the lily or calla flowers. The ribbon or band and the lily or calla flowers may be dispensed with, and the ornament consist of the cross and the representation of wheat.

I claim—

1. The herein-described design for funeral ornament, consisting of the representation in metal of a cross, with the representation on or combined with its surface of a ribbon or band, as represented in the accompanying illustration.

2. The herein-described design for funeral use and ornament, consisting of the representation in metal of a cross, with the representation on or at the sides of its surface of lily or calla flowers, as represented in the accompanying illustration.

3. The herein-described design for funeral ornament and use, consisting of the representation in metal of a cross combined with the representation of wheat, as represented in the accompanying illustration.

4. The herein-described design for funeral ornament and use, consisting of the representation in metal of a cross combined with the representation of a fuchsia flower, as shown in the accompanying illustration.

CHARLES H. LEARNED.

Witnesses:

C. W. MANN,
WILBUR F. DAVIS.